US00D688851S

(12) **United States Design Patent**
Parker

(10) **Patent No.:** **US D688,851 S**
(b4) **Date of Patent:** ** **Sep. 3, 2013**

(54) **WRAP**

(76) Inventor: **Nicole Ari Parker**, Manhattan Beach, CA (US)

(**) Term: **14 Years**

(21) Appl. No.: **29/413,142**

(22) Filed: **Feb. 10, 2012**

(51) LOC (9) Cl. **02-07**

(52) U.S. Cl.

USPC **D2/894; D24/189; D2/627**

(57) **CLAIM**

The ornamental design for a wrap, as shown and described.

DESCRIPTION

FIG. 1 is a top view of Embodiment 1 of the wrap showing my new design thereof;

FIG. 2 is a bottom view thereof;

FIG. 3 is a top view of Embodiment 2 of the wrap showing my new design thereof; and,

FIG. 4 is a bottom view thereof.

The wrap has a nominal thickness.

The dash, dash lines shown in FIGS. 1–4 of the wrap represent surface pattern and are part of the claimed design.
